Primary Examiner — Thomas Johannes*Assistant Examiner* — Jasmine Mlinarcik(74) *Attorney, Agent, or Firm* — AdamsIP, LLC; J. Hunter Adams; Gary N. Stewart(57) **CLAIM**

The ornamental design for an odor blocking pair of trunks, as shown.

DESCRIPTION

FIG. 1 is a front perspective view of an odor blocking pair of trunks incorporating our new design with the wearer's left side adhesive strips disengaged;

FIG. 2 is a back perspective view thereof;

FIG. 3 is a front elevation view of the odor blocking garment with the adhesive strips engaged;

FIG. 4 is a back elevation view thereof;

FIG. 5 is a top plan view thereof;

FIG. 6 is a bottom plan view thereof; and,

FIG. 7 is a side elevation view thereof.
